(57) **CLAIM**

The ornamental design for an insulated food tray lid, as shown and described.

DESCRIPTION

FIG. 1 is an isometric view from above of an insulated food tray lid showing our design;
 FIG. 2 is an isometric view from below thereof;
 FIG. 3 a top plan view thereof;
 FIG. 4 a bottom plan view thereof;
 FIG. 5 a front elevational view thereof;
 FIG. 6 a side elevational view thereof;
 FIG. 7 is an isometric view from above thereof similar to FIG. 1; and,
 FIG. 8 is a front elevational view from above thereof similar to FIG. 5.
 The broken line showing is for illustrative purposes only and forms no part of the claimed design.
